UNITED STATES PATENT OFFICE.

WILLIAM DORIETY AND CHESTER MACARTHUR, OF PATERSON, NEW JERSEY.

TERRY LOOM.

Application filed February 17, 1923. Serial No. 619,585.

To all whom it may concern:

Be it known that we, WILLIAM DORIETY and CHESTER MACARTHUR, citizens of the United States, residing at Paterson, in the county of Passaic and State of New Jersey, have invented certain new and useful Improvements in Terry Looms, of which the following is a specification.

This invention relates to those looms for weaving terry fabrics in which the reed is pressed backward in the batten for a suitable number of picks, during which the terry warp is floated, and then, the terry warp being again bound in by the weft, the reed is returned to its normal position so that the first time it beats up thereafter it slides the intervening weft forward on the main warp and thereby packs it up to the cloth and incidentally causes the floated warps to assume the form of loops, it being understood that for this latter purpose the terry warp beam rotatively yields independently of the main warp beam.

One object of this invention is to provide a terry loom having a simple, inexpensive and reliable combination of parts whereby an endless variety of designs or patterns may be woven. Another object is to make it possible, by changes readily effected, to apply a terry motion to any ordinary loom.

In the drawings,

Fig. 1 is a vertical sectional view of a loom embodying the present invention taken on line 1—1, Fig. 2;

Fig. 2 is a sectional front elevation of the left-hand end-portion thereof;

Fig. 3 is a plan of the forward portion of the loom;

Figs. 4 and 5 are vertical sectional views through the batten and reed-structure, showing the means for controlling the latter in its two main positions;

Fig. 6 is a plan of certain parts of said means, the batten appearing in horizontal section; and

Fig. 7 is a front elevation of certain parts appearing in Fig. 6.

The loom frame *a*, its breast beam *b*, the lay swords *c* upstanding from and secured to the rock shaft *d*, the lay or batten *e* carried by the lay swords, the crank shaft *f* with the cranks of which the batten-including structure *d*, *c*, *e* is connected by the pitman *g*, and the cam shaft *h* are or may be all the same as in any ordinary loom. On the loom frame is arranged a pattern

mechanism, here in the form of any ordinary dobby and used to manipulate the harness (not shown) of the loom. The dobby consists of a frame *i* in which are fulcrumed jacks *j* to which the harness cords are adapted to be attached, *k* being levers pivoted to the jacks and having upper and lower pivoted hooks *l* adapted to be caught and pulled outward, to move the jacks outward, by the upper and lower knives *m* which are caused by suitable means of well known construction and not shown to reciprocate in opposite directions; and *n* are the lifting wires for the respective hooks *l* adapted to be raised by the levers *o* which are made to rise and fall by the pins *p* of a pattern chain *q* which extends over a cylinder *r* that is rotated step by step by any suitable means (not shown).

The reed structure includes the reed *s*, the upper and lower horizontal bars *t* *u* in which the reed is set and end brackets *v* connecting these bars. The lay swords have attached to them brackets *w* affording pivots at *x* (Figs. 3, 4 and 5) for the reed structure, the pivots being actually engaged in holes in the end brackets *v*. The reed may swing backwards on its pivots subject to the pressure of spring plungers *y* arranged in suitable housings *z* on the lay swords.

Bolted to the back of the bar *u* at each end of the reed structure is a fitting *2* in which is pivoted to move up and down a latch in the form of a hook *3* which projects through a slot *4* in the batten and whose shoulder *3a*, when the reed structure is fully forward, may abut a wear plate *5* set in the front of the batten and slotted to receive the hook. This wear plate is secured to the front of the batten by a screw *6* and also by a lag screw *7* which has a long rearward extension *8* received by a horizontal hole *9* in the bar *u* of the reed structure, which hole is elongated transversely of itself and vertically lateral lost motion of the reed structure otherwise possible at the pivots *x* is prevented by the extensions *8* of the lag screws *7*.

At the under side of the batten are secured two brackets *10* in which is arranged a rock shaft *11* having two levers *12* fixed thereon. At their forward ends these levers have pivoted thereto upstanding push rods *13* which are guided in holes in a ledge *5a* projecting from the wear plate and each of which has a rounded head *13a* on which the

corresponding hook 3 rests. The end of the hook is formed with a notch 3^b. To the rear end of one of the levers 12 is pivoted a rod 14 which depends from the lever. 5 The lower end of the rod 14 is connected with a lever 15 fulcrumed in a bracket 16 on the loom frame, the connection being a pivotal one as shown, and being close to the shaft *d* so that when the batten-including structure *d* *c* *e* rocks its movement will not result in appreciable movement of the latch through parts 14, 12, 13. This lever is normally held depressed by a spring 17 which acts through the parts 15, 14, 12 and 10 13 to hold the hook 3 normally elevated.

One of the jacks *j* is set aside for elevating the lever 15. It is connected with this lever by the flexible connection 18 which extends over a suitable roller on a bracket 19 on the frame and includes a spring 20 (stronger than spring 17) and also a turn buckle 21 whereby the length of said connection may be adjusted. We avoid undesirable back and forward movement, with 20 the batten including structure, of the connection 18, by attaching this connection to a lever 15 and operatively connecting this lever with the latch 3 through the connection 14, 12, 13 which is attached to lever 15, as 25 stated, close to the fulcrum *d* of the batten including structure.

In plates 22 secured to the back of the breast beam are screwed the shanks of daggers 23 arranged in the vertical planes of the 30 hooks 3; they may be adjusted, by screwing, toward and from the hooks and when so adjusted secured in their new positions by the lock nuts 24. When the hooks are in their depressed positions and the batten swings forward they will engage in their notches 3^b the daggers and so the reed structure will be pressed backward.

As stated the hooks 3 are normally urged upward by the springs 17, so that the shoulders of the hooks engage the wear plates 5 and the reed is held up to its work, in consequence of which it would beat up to the fell of the cloth in the ordinary way. If the pattern chain *q* "calls" the lever 15 40 through connection 18, then the hooks will be allowed (by gravity) to fall, coming into such positions that each time the batten beats up they will impinge against the daggers, and, being clear of the wear plates, will press back the reed structure, the terry warp being meanwhile floated. In this way the terry, or looping of the terry warps, is produced, the loops being developed when, 45 after each period when the reed structure is pressed back, the loom starts to operate for a time with the reed structure held forward. Ordinarily, as explained, the fabric from start to finish would be simple or plain terry (i. e., involving in alternation and 50 throughout the weaving a certain number of

70 picks when floating of terry warp occurs and a certain number of picks when binding in of the terry warp with the main warp occurs). By our invention this terry weaving can be carried on for any selected extent 75 lengthwise of the fabric (the reed structure being alternately pressed back and then held forward, for the number of picks desired to form the loops and bind in the terry warp with the main warp), and then plain weaving 80 can ensue for any desired extent lengthwise of the fabric, the reed being left held forward by the hooks at such times. Thus a pattern will be developed in the fabric in which there will be looped or terry portions 85 extending across the fabric and of any desired width and intervening plain-weave portions of any desired width. Many variations of this are possible especially when groups of the warps at intervals are all of 90 them retained as parts of the main warp, that is, are wound on the main warp beam and so are not subject to the looping action, whereby if crosswise the fabric is alternately 95 formed terry-weave and plain-weave, rectangular terry figures will be produced.

Our invention makes it possible to convert an ordinary loom, not designed to weave terry, into a loom designed to weave either plain terry or patterned terry without alterations in the loom beyond fitting thereto a repressible reed and the described mechanism on the batten-including structure and breast-beam whereby the reed structure is 100 made to assume in alternation the forward and back positions and also providing the lever 15 and the described connection between it and one of the levers 12 and also between said lever 15 and a jack of the dobby.

105 The spring 20 in the connection 18 permits the calling movement of the controlling jack to occur before the hooks 3 (being down and pressed back by the dagger) have assumed, as the batten recedes, the positions where they are free to rise; therefore, as soon as the hooks assume this position they are sprung immediately into their elevated or locking positions.

110 Having thus fully described our invention, what we claim as new and desire to secure by Letters Patent is:—

A loom including a frame, a reciprocating batten-including structure, a reed-structure 115 backwardly yieldable in the first structure, a gravity depressed latch movable upwardly in said first structure into latching engagement with and thereupon adapted to hold the reed-structure against backward yielding, an up-and-down-movable lever fulcrumed in the batten-including structure between its ends and having at one end means 120 to engage and elevate the latch, a lever fulcrumed in the frame below the first structure, a rod connecting the latter lever with 125

the other end of the first-named lever, the second-named lever being normally depressed and thereby acting through the rod and the other lever to elevate the latch, a pattern-controlled mechanism arranged in the frame above the second lever and including means to exert a pull at intervals and an elastic

extensible pull-transmitting connection connecting said means and the second lever and adapted to lift the latter.

10

In testimony whereof we affix our signatures.

WILLIAM DORIETY.
CHESTER MACARTHUR.
